UNITED STATES PATENT OFFICE.

LOUIS W. GREVE, OF CLEVELAND, OHIO, ASSIGNOR TO THE CLEVELAND PNEUMATIC TOOL COMPANY, OF CLEVELAND, OHIO, A CORPORATION OF OHIO.

FLUID-OPERATED TOOL.

1,198,125.

Specification of Letters Patent. Patented Sept. 12, 1916.

Application filed January 7, 1916. Serial No. 70,785.

To all whom it may concern:

Be it known that I, LOUIS W. GREVE, a citizen of the United States, residing at Cleveland, in the county of Cuyahoga and State of Ohio, have invented certain new and useful Improvements in Fluid-Operated Tools, of which the following is a specification.

The invention relates to fluid operated tools, and has for its primary objects; the provision of a construction of the sleeve valve type wherein the air supply and exhaust chambers are advantageously arranged both from an operative and constructive standpoint, and the provision of improved locking means for securing the handle and body portion from accidental unscrewing and loosening.

One embodiment of the invention is illustrated in the accompanying drawings, wherein—

Figure 1 is a longitudinal section through the hammer employing my invention, Fig. 2 is a section on the line II—II of Fig. 1, 25 and Fig. 3 is a partial side elevation of the hammer at the point of connection between the handle and the cylinder casing, but with the snap ring removed.

The principal parts of the apparatus are as follows; 1 is the handle; 2 is the cylinder casing screw-threaded to the handle at 3; 4 is the hammer piston; 5 is the valve block or cage; 6 is the valve block button or disk clamped between the end of the cylinder casing and the end of the cage 5; 7 is a sleeve valve through which the hammer piston reciprocates; 8 is the locking ring for preventing accidental unscrewing of the cylinder casing and handle; 9 is the locking pin for preventing rotation of the locking ring; 10 is the snap ring for holding the locking ring against longitudinal movement; 11 is the inlet to which a supply hose is attached; 12 is the throttle valve held in closed position by the spring 13; 14 is the rod for operating the throttle valve; and 15 is the trigger for moving the rod 14.

The valve cage 5 is provided with a rearwardly projecting compression chamber 16 which is surrounded by the air supply reservoir or chamber 17 to which air passes from the throttle valve through the passage 18. Air reaches the interior of the valve sleeve behind the hammer piston through the passage 18 and is exhausted from the

front end of the cylinder casing through the passage 19, such passage leading via the groove 20 to the annular exhaust chamber 21 formed between the outer face of the valve cage and the inner surface of the handle. When the sleeve valve is moved to the right from the position shown it uncovers a groove 22, and on the rearward movement of the hammer piston 4 exhaust occurs through such groove 22 and the passage 23 leading to the annular exhaust chamber 21.

The sleeve valve and the port connections whereby it is operated are similar in general arrangement to those shown in my co-pending application, Serial No. 872,063, filed November 14, 1914, and a brief description will be sufficient to indicate the operation of the valve and its relation to the valve cage and the supply and exhaust chambers 17 and 21 in which my invention particularly resides. When the parts are in the position illustrated, air is being admitted from the chamber 17 to the cylinder casing behind the piston via the passage 18 and the piston is passing to the left. At this time air is being exhausted through the passage 19, groove 20 and annular exhaust chamber 21, such chamber having an outlet 24 to the atmosphere. Also at this time the piston 35 covers the port 25 which leads via a passage 26 and port 27 to the pressure receiving surface 28 of the valve. The passage 26 is also extended to the rear in a passage 29 which receives live air from the chamber 17, so that while the piston covers the port 25 pressure is being built up against the surface 28 of the sleeve valve. When this pressure becomes sufficiently great to overcome the pressure on the receiving surface 30 of the valve, it is moved to the right covering the groove 31 and uncovering the groove 22. This movement of the valve 90 shuts off the supply of air to the rear of the piston through the passage 18, at the same time bringing the passage 19 leading to the front end of the piston in communication with the groove 31 via the groove 32. Motive power is thus supplied to move the piston to the right and exhaust occurs from the right hand end of the piston via the groove 22, passage 23, and exhaust chamber 21. When the piston in its movement to the right uncovers the port 25, the pressure on the surface 28 is reduced somewhat and 100

105 110

when the right-hand end of the piston covers the exhaust groove 22 and compression occurs in the chamber 16, the increased pressure on the surface 30 causes the valve to move to the left to the position shown.

It may be further stated with respect to the matter of pressures upon the surfaces of the valve that during the forward movement of the piston (to left) the pressures on the 10 surfaces 30 and 30', are the same, but 30 is the larger so that the valve stays in the position shown until the pressure on the surface 28, as above described, causes the valve to move to right, the force required 15 being of course relatively slight, since the pressures on the surfaces 30 and 31 nearly balance each other. Also when the piston in its movement to the right covers the forward end of the valve, the force required 20 by the compressed air on the surface 30 to shift the valve to the left is slight since there is only exhaust pressure on the surfaces 30', 28 and 28' and these pressures are nearly balanced.

25 The piston is cushioned in its rearward movement by the air compressed in the chamber 16. The port 33 in the rear end of the compression chamber is useful when the machine is operated up-side-down, and 30 the piston happens to be in the compression chamber, in which case the air from the port 33 will give the piston its initial movement. The locating of the supply reservoir 17 around the compression chamber is ad- 35 vantageous, as it gives a relatively large volume of air under pressure close to the point of application of such air tending to steady the running of the machine. This arrangement also tends to compactness, and 40 there is a constructive advantage in having this chamber and the exhaust chamber 21 formed between the opposing surfaces of the cage and handle where the cavities are readily accessible and easily formed. The 45 arrangement and size of the chamber 21 provides for a free exhaust.

An advantage is also involved in having the compression chamber 16 integral with the valve cage block 5 instead of having 50 the rear wall of such chamber formed by a wall of the handle, since any loosening of the handle does not affect the tightness and efficiency of the compression chamber and the piston can never strike the rear 55 wall of the chamber. The use of a valve with imperforate walls having exhaust and admission across the end edges of the valve has a constructive advantage as the valve is simpler and cheaper than those having 60 perforated walls, and there is less danger of cracking which frequently starts in perforate valves at the perforations.

The edges of the locking ring 8 and the 65 handle are provided with opposing projections 34 and 35, each extending around 180

degrees, so that relative rotative movement is prevented when the locking ring is in operative position. The inner surface of the locking ring is provided with a plurality of longitudinal slots 36, and the cylinder casing carries the removable pin 9 whose outer end 38 is formed with flattened sides and eccentric with respect to the body of the pin and adapted to engage one of the slots 36. The elongated flattened end engaging the slot prevents the pin turning on its axis. The plurality of holes 39 for the pin 9 are provided so that it may be adjusted circumferentially of the cylinder casing. As indicated in Fig. 2 these holes are spaced 80 with respect to the slots 36 in the ratio of 3 to 4, so that leaving aside the matter of the eccentric arrangement of the end of the pin, it is necessary to rotate the ring only one-half the distance between two of the 85 slots 36 in order to secure a second connection between the pin and the ring. For instance, if it were necessary to rotate the ring clock-wise half the distance between two slots 36, the pin 9 would give this ad- 90 justment if shifted to the hole to the right of the one which it now occupies. The eccentric arrangement of the end 38 also increases the fineness or range of the adjustment. The two sets of adjustment together 95 divide the spaces between the slots 36 to such an extent that the ring 8 can be made to interlock both with the handle and with the cylinder casing when the parts are screwed tight. The snap ring 10 is open at 100 one side as indicated in Fig. 2, and has one flanged edge in engagement with a groove in the handle and the other with a shoulder on the locking ring 8.

The throttle valve 12 is provided with a 105 plurality of small holes 40, so that when the valve is only slightly depressed, a small quantity of air flows to these openings through the ports 41, the rod 18 fitting its 110 socket in the valve loosely so that the air which passes the openings 40 can flow up into the supply passage 18 and give the machine its starting movement. A further movement of the valve permits a full supply of air from the ports 41 to flow past its 115 upper edge, this being the normal working position of the valve.

What I claim is:

1. In combination in a fluid operated tool, a handle provided with a fluid supply chamber, a cylinder carrying a piston hammer and secured to the handle, a valve cage between the cylinder and handle and provided with a compression chamber projecting into and surrounded by said supply chamber, 120 and a sleeve valve mounted in the case forward of the said compression chamber.

2. In combination in a fluid operated tool, a handle provided with a fluid supply chamber, a cylinder carrying a piston ham- 125

mer and secured to the handle, a valve cage between the cylinder and handle and provided with a compression chamber projecting into the said supply chamber and having its sides and rear end surrounded by said chamber, and a sleeve valve mounted in the cage forward of the said compression chamber.

3. In combination in a fluid operated tool, 10 a handle, a cylinder carrying a piston hammer and secured to the handle; a valve cage at the rear end of the cylinder, a compression chamber having its side and rear walls a part of said cage, and a sleeve valve 15 mounted in the cage forward of the compression chamber.

4. In combination in a fluid operated tool, a handle provided with a fluid supply cham-

ber, a cylinder carrying a piston hammer and secured to the handle, a valve cage at 20 the rear end of the cylinder, a compression chamber having its side and rear walls integral with the valve cage and surrounded by said supply chamber, and a sleeve valve mounted in the cage forward of the said 25 compression chamber.

5. In combination in a fluid operated tool, a handle, a cylinder carrying a piston hammer and secured to the handle, a valve cage at the rear end of the cylinder having integral therewith at its rear end a compression chamber, and a sleeve valve mounted 30 in the cage forward of the compression chamber.

LOUIS W. GREVE.
